UNITED STATES PATENT OFFICE.

ISAAC HERRMANN, OF ELYRIA, OHIO.

WATCHMAN'S TIME-RECORDING MECHANISM.

Application filed June 28, 1923. Serial No. 648,189.

To all whom it may concern:

Be it known that I, ISAAC HERRMANN, a citizen of the United States, residing at Elyria, in the county of Lorain and State 5 of Ohio, have invented a certain new and useful Improvement in Watchmen's Time-Recording Mechanism, of which the following is a full, clear, and exact description, reference being had to the accompanying 10 drawings.

This invention relates to time recording mechanism, and more particularly to mechanism of the clock type used by night watchmen and patrolmen for the purpose of enabling 15 them to make an accurate record of the times at which they arrive at a certain place or places on their rounds or posts, but which will ordinarily prevent any unauthorized person from opening the casing for any 20 purpose, as well as preventing any person from opening the casing without leaving a record of such action. The invention disclosed herein is an improvement upon a recording clock of this general character shown, described 25 and claimed in my Patent No. 1,231,350 issued June 26, 1917.

Among the objects of my invention are: to improve and simplify the construction and operation of the day-selector disk by 30 means of which the recording disk (or other record-receiving element) may be marked by an instrument inserted through the proper aperture in the cover corresponding to the appropriate day of the week (or month); to provide a novel arrangement of 35 shutter for the apertures in the cover for the record-making instrument or device, for the operating arm for the day-selector disk through which the record-marking device is 40 inserted, and for the cover-unlocking mechanism; to provide such shutter with a novel locking means; also to provide a novel construction and mounting for the instrument or device which is employed with the afore- 45 said apertures. Further and more limited objects of the invention relate to the construction and arrangement of parts whereby a simple, economical and reliable device of 50 this character is produced, all of which will be set forth in the specification in connection with the detailed description.

In the drawings Fig. 1 represents a plan view, and Fig. 2 a side elevation, of the complete device or clock, with the cover and shutter closed; Figs. 3 and 4 are front elevations of the device showing, respectively,

the shutter opened and closed; Fig. 5 a view similar to Fig. 1, with the shutter elevated and shown in section; Fig. 6 a view similar to Fig. 2, with the shutter elevated; Fig. 7 a plan view showing the cover wide open to disclose the interior construction; Fig. 8 a bottom plan view of the day-selector disk; Fig. 9 a view similar to Fig. 2 with parts of the shutter broken away; Fig. 10 a sectional 60 side elevation of the device as shown in Fig. 6, the sectional view corresponding to the line 10—10 of Fig. 7; Fig. 11 an enlarged sectional detail corresponding to the line 11—11 of Fig. 5; and Fig. 12 a view in elevation of the form of key or unlocking device for the shutter.

Describing the various parts by reference characters, 1 denotes a cylindrical metal casing having a cover 2 provided with hinged 75 lugs 3 by means of which it is hinged to the lugs 4 projecting from the casing, the pivot pin being indicated at 5. The cover is preferably provided with a rim 2^a adapted to overhang the top of the casing.

The casing is preferably formed as a casting and has opposite the hinge lugs a fin or projection 6, with a pair of vertical ribs 7 and 7^a extending downwardly on each side of such projection, the rib 7^a having a recess 85 7^b extending thereacross and the rib 7 having a similar recess 7^c which does not extend entirely across the latter rib but which terminates within the outer edge or surface thereof. The recesses 7^b and 7^c constitute 90 a seat for the key by which the shutter is unlocked.

The cover is provided with a series of apertures 8 extending generally radially thereof. Seven such apertures are shown, 95 one for each day of the week, each aperture being adapted to register with one of the seven annular day spaces shown on the record-receiving element (shown as a recording disk 9) cooperating therewith and to 100 which further reference will be made herein-after. The apertures are preferably formed in a thickened or ribbed portion of the cover, indicated at 8^a. Projecting upwardly from the cover is a lug 10 to which a chain 11 is 105 connected, the said chain having secured thereto a punching tool 12 having a pointed end 12^a adapted to puncture, or make a suitable depression in, the record disk 9, the latter being preferably of paper, with the 110 part beneath said apertures 8 supported by an anvil 14 which is secured to the inside of

the casing by a flange 14^a and which is provided with apertures 14^b registering with the apertures 8 and allowing the point 12^a of the tool to prick the disk (see Figs. 7 and 11). The tool 12 is provided with a head 12^b which receives and secures in place the upper end of a helical spring 13, which spring normally holds the pin 12 in elevated position with its point away from the disk 9, whereby the point of the tool is prevented from sticking in the aperture made in such record disk and thus tearing the latter.

The cover is also provided with an arcuate slot 15 for the reception of the operating arm or projection for the day-selector disk, which will be described hereinafter. It is also provided with a locking lug 16 extending between the ribs 7, 7^a and above the fin or projection 6.

Pivoted to a lug 17, preferably located at the central portion of the cover, is a shutter, indicated generally at 18, the pivot being indicated at 17^a. The shutter comprises an elongated base plate having a downwardly extending rim flange 18^a, which flange is adapted to receive therewithin, when the shutter is lowered, the rib 8^a with its apertures 8, and the tool 12 and its anchoring lug 10 and chain 11; also the upper end of the arm or projection for the day-selector disk. At its front or swinging end, the shutter is provided with an integral flap or extension 18^b, which is adapted to extend across and cover the front edges of the ribs 7, 7^a. Secured to the inner or rear face of this flap is a flat spring detent 19 the upper end of which is bent inwardly or rearwardly and is of such length as to catch beneath the locking lug 16. The front face of the locking lug is beveled downwardly and forwardly, as indicated at 16^a. This beveled surface cooperates with the rearwardly directed end 19^a of the spring plate detent to force the latter outwardly and forwardly as the shutter is swung to its lowered position. As soon as the upper end of the detent clears the lower end of the inclined face 16^a, it snaps beneath the lug and holds the shutter in locked position.

For the purpose of unlocking the shutter the tool or key shown in Fig. 12 is provided. This tool or key, indicated generally at 20, has a cylindrical end 20^a which is adapted to be seated in the recesses 7^b and 7^c, with the lugs 20^b presented inwardly or rearwardly, the recess 7^b being provided with an extension 7^d through which the lugs may be inserted into the space or recess between the ribs. By rotating the key, the lugs 20^b will strike the detent spring and disengage it from beneath the locking lug 16, whereupon the shutter may be swung upwardly about its pivot 17^a, thus permitting access to all of the parts covered thereby.

Reference has been made to the record

sheet or disk 9. This sheet or disk is provided with radial lines defining hour spaces, twelve such spaces being shown. In addition, it is provided with seven concentric annular spaces, corresponding to the days of the week. Each record disk is supported on top of a platform 21^a carried by the final shaft of a clock-mechanism (not shown) such as is usually employed with recording clocks of the type to which this invention relates. The record sheet or disk is conveniently applied and secured in place by having a central aperture therein adapted to receive a central post or extension 21 of the final drive shaft, which central post may be supported by the platform on which the central part of the record disk is mounted. The disk is conveniently secured in place by means of pins 21^b projecting upwardly from the platform and a cooperating disk 22 having a central hub cap 22^a by means of which it may be slipped over the post 21, the disk being provided with slots to permit the passage of the pins through the record disk. This construction affords a simple, efficient, and economical manner for detachably securing the record disk in place.

As pointed out hereinbefore, the disk is arranged so that it will be rotated across the anvil 14, enabling the tool 12 to punch upon the proper day segment of the disk the hour of the day at which the record is made.

The cover is also provided with a locking post 23, which is adapted to enter a vertical slot 24 formed between a pair of projections 25 and 26 extending inwardly from the inner face of the casing, one of said projections being shown as provided with a slot 27, which may receive a striker adapted to perforate the dial or record sheet whenever the cover is unlocked, as shown, described and claimed in my patent hereinbefore referred to. As is the case with the construction disclosed in said patent, the lug 23 is provided with a perforation for the locking bolt 28, which locking bolt is adapted to be operated by a key inserted in a short barrel 29 projecting outwardly from the casing and located in the recess between the ribs 7 and 7^a. This barrel and recess are arranged to be covered by the depending extension plate of the shutter, so that the cover cannot be unlocked and opened without opening the shutter; and, in the event that it is so opened, the striker will pierce the record sheet and thus show the fact and the time of the opening of the casing (as set forth in my earlier patent.)

Journalized upon a stud 30 depending from the central portion of the inner face of the cover is the day-selector disk 31. This disk is provided with seven apertures 31^a, radially and angularly spaced, and preferably arranged in a curve, so that, by partial successive rotary steps of the disk, the apertures

31^a may be brought successively into register with the apertures 8, beginning with the central or innermost aperture of each series. The disk is provided with notches 32, 32^a, 5 32^b, 32^c, 32^d, 32^e, 32^f, 32^g adapted to be engaged by a spring detent pawl 33. The notch 32 is adapted to be received by the end of the detent pawl at the time when the innermost aperture 31^a is in register with 10 the corresponding aperture in the cover, at which time the feeding pawl 34 will be in engagement with the notch 32^b.

The feeding pawl 34 is carried by a radial arm 35 pivoted on the stud 30 by means of 15 a central hub or enlargement 35^e and a washer 36. The arm 35 is thickened at one side and provided with a radial series of apertures 35^a, which register with the apertures 8 in the cover and with which the apertures 31^a are adapted to register. The arm 35 is also provided with an arcuate extension 35^b to which a spring 37 is secured, the opposite end of the spring being secured to a lug 37^a on the cover. The operating arm or 20 projection 38 for the arm 35 (to which reference has been made hereinbefore) projects through the arcuate slot 15 in the cover and is adapted to be covered by the shutter 18, when the latter is lowered.

30 With the parts arranged as described, it is believed that the operation will be readily understood. Assuming that the platform and post 21 are driven by the usual clock-mechanism so that the recording disk 9 will 35 make its revolution in the desired interval of time (say 12 hours), the watchman or patrolman, arriving at the station where this recording device is located, will first insert the key 20 in the recesses 7^b and 7^c and, by 40 rotating the same in the appropriate direction will disengage the end 19^a of the detent spring 19 from the locking lug 16; this will enable the watchman to swing the shutter upward to the position shown in Figs. 3 and 45 6. He can then punch or indent the record for the appropriate time of the day and day of the week by inserting the point of the punch or tool 12 into the appropriate aperture 8 in the cover and pressing downwardly 50 on the head. When the pressure is released, after the punching operation, the spring 13 holds the point out of contact with the disk and in readiness for the next operation on that particular day, the tool or punch being 55 retained in such inserted position by the shutter.

If it is necessary to advance the day-selector disk 31, the operator can do so by grasping the arm or projection 38 and moving the 60 ratchet-carrying arm 35 in the appropriate direction. The length of the slot 15 is such as to enable the disk to be moved one step, and the spring detent 33 will enter the appropriate notch and retain the disk in this 65 adjusted position. The watchman or pa-

trolman can then perforate or indent the record disk only by inserting the tool into the appropriate registering apertures 8, 31^a and 35^a, corresponding to the proper day of the week.

Should it be necessary to obtain access to the interior of the casing, this may be done by unlocking the shutter and inserting the key into the barrel 29, thereby disengaging the bolt 28 from the post 23. Where a 75 striker is provided, such as shown in my patent hereinbefore referred to, the fact and the time of so opening the casing will be shown by the perforation of the record disk in line with the slot 27.

When the day-selector disk shall have been advanced to bring the feeding pawl 34 into the last notch 32^g, no further movement of the disk by the said pawl will be possible, the outermost aperture 31^a in the disk at this 80 time registering with the outermost apertures 8 and 35^a. To reset the selector-disk, the operator can turn the same by hand until the detent pawl 33 snaps into the recess 32, at which time the innermost apertures 8, 85 35^a and 31^a will be in register. At this time, the record disk can be removed and a new one inserted and clamped in an appropriate 90 position upon the platform 1^a.

The recording device described and illustrated herein is simple in construction and cheap of production, but accomplishes in a very efficient manner the objects for which it is designed and intended.

Having thus described my invention, what 100 I claim is:

1. In a recording device, the combination with a casing, and means secured upon the exterior thereof, operating thru holes in said casing, to mark a record therein, of a 105 shutter movably connected to said casing and arranged to cover the said holes and the said means, and means for locking the said shutter in such covering position.

2. In a recording device, the combination with a casing having holes therein, of a tool insertible thru the said holes for marking a record in said casing, an arm for moving the said record, projecting thru said casing, a shutter movably supported by said casing and adapted to cover the holes in the casing, the said tool, and the said arm, and means for locking the said shutter in closed or covering position.

3. In a recording device, the combination with a casing having a cover with holes therein, of a tool attached to the cover and adapted to be inserted in said holes to mark a record in the casing, means projecting thru said cover for operating a selector in the casing, means for locking the said cover, a shutter movably supported by the casing and adapted to cover and shield the holes therein, the tool, the selector-operating projection and the cover-locking means, and 120 125 130

means for locking said shutter in shielding or covering position.

4. In a recording device, the combination of a casing, a record-receiving element in said casing, and means for moving the same, the said casing having a cover provided with a series of apertures therein arranged in operative relation to the said element, also means for locking the cover, the said casing having a recess provided with means therein whereby the cover may be unlocked, a locking projection carried by the cover and overhanging the recess, a shutter pivotally connected to the cover and adapted to shield the apertures therein and having a flap or extension adapted to cover said recess, the said flap or extension having a detent adapted to engage the flap on the cover, and key-operated means for disengaging the detent from the projection, whereby the shutter may be moved to uncover the detent and recess.

5. The combination stated in claim 4, said detent projecting upwardly and adapted to engage beneath the said projection on the said cover.

6. In a recording device, the combination of a casing, a record-receiving element in said casing and means for moving the same, said casing having a cover, means carried by said cover and within said casing for locking said cover in closed position, a locking projection carried by the cover, a pair of ribs projecting outwardly below said projection and forming a recess therebetween, means located between said ribs for unlocking said cover, the said ribs having recesses therein forming a seat, a key insertible through a slot in one of said ribs and arranged to be seated in the recesses thereof, and a shutter pivoted to the cover and having a depending flap or extension adapted to co-act with and cover the outer edges of said ribs and having an upwardly extending detent adapt-

ed to engage said cover projection and to be 45 disengaged therefrom by rotation of said key.

7. In a recording device, the combination of a casing, a record receiving element in said casing and means for rotating the same, said element having thereon annular segments, said casing having a series of radial apertures for said segments, a selector disc rotatably mounted in front of said apertures and having series of apertures therein 50 arranged, by movements of said disc about its axis, to register each with one of the first-mentioned apertures, ratchet mechanism for operating the said disc, the said mechanism comprising an arm concentric with said disc and having a pawl adapted to engage the periphery of said disc, said arm being provided with a series of radial apertures 55 adapted to register each with one of the first-mentioned apertures, a spring connected to said arm, an operating projection for said arm extending through a slot in the said casing, and a detent cooperating with the said disc.

8. In a recording device, the combination 70 of a casing having a cover, a record-receiving element rotatably mounted in said casing and having spaced divisions therein corresponding to time intervals, the said cover having apertures arranged in operative relation to such spaced divisions, respectively, a selector disc rotatably mounted on the underside of said cover and having apertures therein adjusted each to be brought 75 into register with an aperture in the cover, and means projecting through said cover for moving the said disc, said means including an arm having holes adapted to be registered with the apertures in said disk.

In testimony whereof, I hereunto affix my 85 signature.

ISAAC HERRMANN.
